FENCE CONSTRUCTION

Frank G. Carrel, Western Springs, Ill., assignor,
by mesne assignments, to Calumet Steel Com-
pany, Chicago, Ill., a corporation of Delaware

Application July 12, 1930. Serial No. 467,409

3 Claims. (Cl. 189—29)

My invention relates to fence construction and more particularly to dirt-set end or corner structures which are preferably employed in the indicated locations of fence lines, although readily adaptable for use along other portions of such lines.

One object of my invention is to provide a structure of the above character which may be erected in position with a minimum of digging, free from any necessity for concrete or other auxiliary settings, and which is characterized by a degree of strength and rigidity of placement that insures a maintenance of a taut, straight fence line.

15 A further object is the devising of a structure of this type which is fabricated at the place of use from a plurality of steel angle pieces and plates that offer a high resistance to erosion and a maximum of strength per unit weight of the 20 material, the assembly being effected quickly, easily and at a low rate of cost.

25 A further object is the provision of a metallic fence post which is suitably braced by auxiliary members to maintain its proper upright position against the pull of the fence, these members being so associated with the posts that their capacity for acting as effective braces is unaffected by the unevenness of the ground, the construction therefore being highly versatile and always 30 insuring a fence that is correctly placed and satisfactorily strengthened against the stresses and strains prevailing in this type of service.

35 My invention is concerned more particularly with fences employing metallic posts and is intended to provide a secure anchorage therefor to the end that the posts will maintain their vertical positions and the fence its original tightness and consequently its original neatness of appearance over a long period of time. The design of 40 this structure permits its assemblage at the point where erected through a simple bolting of the parts together, each step in the assembly substantially acting as a guide or gauge to determine the correct position of the next piece to be applied. The principal post of the structure is the 45 only member requiring the digging of a hole, the shorter anchor posts which neutralize the larger part of the pull on the main posts through braces 50 and plate members as hereinafter described being driven into position.

These and further objects of my invention will be set forth in the following specification, reference being had to the accompanying drawing, 55 and the novel means by which said objects are

effectuated will be definitely pointed out in the claims.

In the drawing:

Figure 1 is a perspective view of the corner of a fence line showing my improved construction as applied to the corner post. 60

Fig. 2 is an enlarged section along the line 2—2 in Fig. 1, looking in the direction of the arrows, and showing the combined foot and anchor construction employed at the base of the corner post. 65

Fig. 3 is an enlarged view, looking in the direction of the arrow 3 in Fig. 1, and showing the manner of securing one end of the brace member to the corner post. 70

Fig. 4 is an enlarged section along the line 4—4 in Fig. 1, looking in the direction of the arrows, and showing the manner of securing the opposite end of one of the brace members to its companion anchor post. 75

Fig. 5 is a view similar to Fig. 1, but showing the construction as applied to an end post in a fence line. 80

Referring to Fig. 1, my improved fence construction comprises a main or corner post 10, diagonal braces 11, anchor posts 12, a combined foot and anchor member 13 which is composed of a plurality of pieces and attached to the lower end of the post 10, as described more particularly hereinafter, and anchor plates 14 and 15 secured, respectively, to the corner post 10 and anchor post 12. Except for the plates 14 and 15, the above parts are preferably formed of steel angle pieces as providing greater strength and affording more resistivity to the action of moisture and ground acids, but it is contemplated that these several parts, including the above plates, may be varied as regards form and choice of material used without affecting the primary conception of this invention, which resides essentially in the manner in which these several parts are assembled together. The exposed parts of the structure may be painted for decorative purposes as desired and the embedded portions may be additionally covered with protective coatings of various kinds. 90

As shown in Fig. 1, a plurality of angle pieces 16 are used to form the combined foot and anchor member 13, these members being assembled and secured to the lower or embedded end of the post 10 with two of said pieces bolted together and to one limb 17 of the post 10 by bolts 18. Another piece 16 is similarly bolted to the other limb 19 of said corner post, so that the lower end of the latter is thereby provided with an 100 105 110

enlarged surface which enables the post to stand upright during the assemblage of the structure and also functions, when the earth is thereafter tamped around the corner post to firmly anchor the same from displacement from its original, vertical position. Above the member 13, and at a predetermined distance therefrom, but within the embedded portion of the post 10, a pair of the anchor plates 14 is secured to said post by bolts 20, a plate being secured to each one of the limbs 17 and 19 of said post.

A hole 21 is thereafter dug having a cross-sectional profile generally corresponding to that defined by the marginal edges of the member 13 and of a depth determined by the portion of the post 10 to be embedded. The post 10 is then inserted in the hole 21 with the member 13 resting on the bottom thereof and with the anchor plates 14 normally disposed to the direction of the fence lines for a purpose hereinafter explained. The hole 21 may then be filled with dirt and stones and suitably tamped, after which the upper ends of the diagonal braces 11 are secured to the inner faces of the limbs 17 and 19 by bolts 22 and the lower end of each brace is permitted to drop substantially to the ground line, this dropping of the braces determining the location of the coacting anchor posts 12 which are then driven into the ground to be substantially embedded therein and the upper end of each post 12 and the lower end of each brace 11 are secured by a bolt 23. Prior to driving each post 12, the latter may have affixed thereto a pair of anchor plates 15 by bolts 24, said plates being suitably disposed between the ends of each anchor post so as to provide the greatest resistance to displacement of the latter under the strain produced by the fence line. The corner structure is now completed, whereupon the usual wire 26 may be secured to the post 10 in the usual manner.

A fence structure of this type is susceptible of simple fabrication, the separate parts being stored until needed, followed by their assemblage as desired at the places used. All parts are drilled to receive the several bolts and the several parts fit each other accurately to facilitate a rapid assembly. The relation of the angle pieces to each other insures the obtaining of a rigid, sturdy construction that maintains the fence line in a taut, straight condition, and this result is obtained without any necessity for cumbersome, bulky settings, such as concrete and the like. Moreover, each part as assembled acts substantially as a guide to locate the correct position of the succeeding part, so that the structure may be assembled easily and quickly by unskilled labor. The amount of labor involved is also considerably lessened, with respect to similar structures which are characterized by an equivalent rigidity of position, by the necessity of digging only one hole, since the other embedded parts are positioned by simple driving operations. The combined foot and anchor member 13 adequately resists any tendency of the corner post 10 to be moved out of its vertical position, or to be pulled bodily upward, while the anchor plates 14, by reason of their location with respect to the direction of the joining fence lines, effectively prevent any tendency of the corner post 10 to bow between its ends under the pull of the fence. A similar function is performed by the anchor plates 15 on the corner post 12, since the stress operating along each brace 11 is effectively counteracted by the large surface presented by the anchor plates

15 to the ground within which they are embedded.

Owing to its capacity for free movement during the assembly of the structure relative to the post 10, each brace 11 accurately determines the position of its corresponding anchor post 12, regardless of the unevenness of the ground, whether sloping downwardly away from the post 10 or directed upwardly therefrom, it only being necessary, as set forth above, to simply drop the lower end of the brace 11 on the ground and thereafter drive the anchor posts 12 in position for securing their adjacent ends together. If, in driving, the anchor post 12 should strike an obstruction or become twisted for any reason, the post may be easily pulled into correct line by unbolting the upper end of the corresponding brace 11 from the post 10 and securing the lower end of said brace to the upper end of the anchor post in question and thereafter using such brace as a lever to correctly position the indicated anchor post.

In Fig. 5, the structure illustrated refers to the end post of a fence line, the manner of assembling and the parts necessary therefor being identical with those shown in Fig. 1. In this situation, it is only necessary to brace the corner post in one direction, as contrasted with the dual bracing shown in Fig. 1, so that it is only required to employ a single brace 11, a single anchor post 12, and a single anchor plate 14 on the corner post. It is also contemplated that long fence lines may require at certain intervals the interposition of a construction such as is shown in Fig. 5, with the addition of another diagonal brace and anchor post located on the opposite side of the main post from that shown in said figure, thus bracing the post in opposite directions along the same fence line.

While I have shown one set of elements and combinations thereof for effectuating my improved fence construction, it will be understood that the same is intended for purpose of illustration only and in no wise to restrict my arrangement to the exact forms and structures shown, for many changes may be made therein without departing from the spirit of my invention.

I claim:

1. A fence post of angle section for a fabricated fence construction having a combination foot and anchor member, said member comprising a plurality of short lengths of angle pieces, the vertical limbs of two of said pieces being secured to one limb of said post and the vertical limb of a third piece being secured to the other limb of said post, the other limbs of said pieces forming an extended supporting footing for the post.

2. A fence post of relatively small cross section having a combination foot and anchor member, said member comprising a plurality of short lengths of angle pieces, the vertical limbs of two of said pieces being secured to one of the sides of the post and the vertical limb of a third piece being secured to another side of said post, the other limbs of said pieces forming an extended supporting footing for the post.

3. A fence post of relatively small cross section having a combination foot and anchor member, said member comprising a plurality of short lengths of pieces, each of which has a pair of normally disposed sides, one of which is horizontal, two of the pieces being secured to one side of the post and the other piece to another side of the post, the horizontal sides of said pieces forming an extended supporting footing for the post.

FRANK G. CARREL.
